CLAIM

I claim the ornamental design for a structural panel with an ornamental surface, as shown and described.

DESCRIPTION

FIG. 1 is a perspective view of a structural panel with an ornamental surface, showing my new design;

FIG. 2 is another perspective view thereof;

FIG. 3 is a side perspective view thereof;

FIG. 4 is a top plan view thereof;

FIG. 5 is an enlarged detailed view of FIG. 4;

FIG. 6 is a cross sectional view taken along line 6-6 in FIG. 5; and,

FIG. 7 is a cross sectional view taken along line 7-7 in FIG. 5.

The dashed broken lines in the drawings illustrate portions of the article that form no part of the claimed design.

1 Claim, 5 Drawing Sheets
